Primary Examiner — Dana Meyrow(74) Attorney, Agent, or Firm — Meunier Carlin & Curfman LLC(57) CLAIM

We claim the ornamental design for a bottle, as shown and described.

DESCRIPTION

FIG. 1 is a perspective view of a bottle, in accordance with our new design;

FIG. 2 is a front elevation view thereof;

FIG. 3 is a back elevation view thereof; and,

FIG. 4 is a top view thereof.

The evenly-dashed broken lines in the drawings illustrate the portions of the bottle that form no part of the claimed design. The dot-dash broken lines in the drawings define the bounds of the claim and form no part thereof.
